UNITED STATES PATENT OFFICE.

JOHN SAMUEL HUNTER, OF COALINGA, CALIFORNIA.

DOUBLE-ACTING PUMP.

Application filed March 1, 1926. Serial No. 91,547.

This invention aims to provide a simple but effective pump, the sliding pistons of which will operate to elevate liquid not only upon the up-stroke, but on the down-stroke, 5 as well.

It is within the province of the disclosure to improve generally and to enhance the utility of devices of that type to which the invention appertains.

With the above and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed, without departing from the spirit of the invention.

In the drawings:

Figure 1 shows in elevation, a device constructed in accordance with the invention;

Figure 2 is a longitudinal section showing the upper part of the device;

Figure 3 is a longitudinal section showing the lower part of the device;

Figure 4 is a cross section on the line 4-4 of Figure 2;

Figure 5 is a cross section on the line 5-5 of Figure 3.

The device comprises an outer barrel 1. The outer barrel 1 is enlarged as at 2, at its upper end, and threaded at 3, so that it may be mounted in a well casing (not shown).

An inner barrel 4 is located within the outer barrel 1, in fixed relation thereto. The parts specified are fixed with respect to each other, because the inner barrel 4 is threaded into an annular partition 5 which, in its turn, is threaded into the lower end of the outer barrel 1. The inner barrel 4 has apertures 7 which are located above the partition 5. A foot 8 is mounted on the lower end of the outer barrel 1. The foot 8 carries a cage 9.

Within the cage 9, there operates a downwardly closing valve 10. The valve 10 cooperates with a seat 11, in the foot 8. There are openings 6 in the partition 5.

A ring 12 is threaded into the upper end of the outer barrel 1. The ring 12 has any desired number of relief ports 14. A thimble 15 is threaded into the ring 12. The thimble 15 encloses a packing 16. The parts 15 and 16 constitute a gland. The thimble 15 has an outstanding flange 17 at its upper end. The relief ports 14 are closed by an

annular valve disk 18 slidable on the thimble 15. The disk 18 is pressed down on the ring 12 and on the upper end of the outer barrel 1, in closed relation to the ports 14, through the instrumentality of a compression spring 19. The compression spring 19 surrounds the thimble 15, and the upper end of the spring abuts against the flange 17 of the thimble.

A tube 20 slides within the packing 16 of the gland, and the tube 20 also has a tight sliding fit around the inner barrel 4. There are openings 21 in the tube 20. When the tube 20 is at the limit of its downward stroke, the openings 21 are closed by the inner barrel 4. Near to its upper end, the tube 20 has other openings 22. A piston 23 is mounted on the lower end of the tube 20. The piston 23 slides in contact with the inner surface of the outer barrel 1. The piston 23 may be denominated a first piston, and a second piston, marked by the numeral 24, slides within the inner barrel 4. The second piston 24 is carried by a cage 25. Within the cage 25 operates a ball valve 26 cooperating with a seat 27 in the cage, the ball valve closing downwardly. The cage 25 is mounted on the lower end of an operating member 28, which may be a rod. The rod 28 is held by a securing element 29 in the hub 30 of a head 31. The head 31 is threaded into the upper end of the tube 20, and, thus, the pistons 23 and 24 are connected for simultaneous movement. There are openings 32 in the head 31.

On the up-stroke, the piston 24 sucks liquid into the inner barrel 4, the valve 10 opening, and the valve 26 closing. The piston 23 sucks liquid into the space between the outer barrel 1 and the inner barrel 4, the liquid entering either through the openings 6 in the partition 5, or through the apertures 7 in the inner barrel 4, or by way of both of these sources. When the pistons 24 and 23 move downwardly, the valve 10 closes, and the valve 26 opens. The piston 23 forces the liquid which is between the outer barrel 1 and the inner barrel 4 through the apertures 7 and upwardly past the valve 26, and when the pistons 24 and 23 move upwardly again, the piston 24 boosts the column of water in the inner barrel 4, and the water pours out through the openings 21 in the tube 20, as those openings arrive upon the upper end of the thimble 15. In the event that liquid happens to leak in between the

piston 23 and the ring 12, the pump will not hammer and knock, because, on the up-stroke, the piston 23 will lift the imprisoned water, force it through the relief ports 14, and cause the water to raise the valve 18, for the relief of the water, the spring 19 serving to seat the valve 18 again on the down-stroke.

What is claimed is:

10 A pump comprising an outer barrel, a foot valve for the outer barrel, an inner barrel fixed within the outer barrel, a tube slidable upon the inner barrel and provided with an

outlet, a first piston carried by the tube and slidable between the barrels, a second piston 15 slidable within the inner barrel and provided with a downwardly closing valve, means for connecting the second piston to the tube to move therewith, and a spring-seated relief valve which operates at the upper end of the 20 outer barrel, externally of the tube.

In testimony that I claim the foregoing as my own, I have hereto affixed my signature.

JOHN SAMUEL HUNTER.
